UNITED STATES PATENT OFFICE.

HERBERT E. MILLSPAUGH, OF FLINT, MICHIGAN.

DESIGN FOR AN ADVERTISING SIGN.

Application filed January 18, 1924. Serial No. 8,348. Term of patent 7 years.

To all whom it may concern:

Be it known that I, HERBERT E. MILLSPAUGH, a citizen of the United States, residing at Flint, in the county of Genesee and State of Michigan, have invented a new, original, and ornamental design for an advertising sign in the form of a miniature windmill, provided with the usual revolving propellers upon which advertisements are to be applied, the wall surfaces of the wind-

mill likewise providing spaces for additional signs, reference being had to the accompanying drawing, forming part thereof.

The figure is a perspective view of an advertising device.

I claim:

The ornamental design for an advertising sign, as shown.

HERBERT E. MILLSPAUGH.
